UNITED STATES PATENT OFFICE.

CHRISTIAN C. SCHEERER, OF TUTTLINGEN, GERMANY, ASSIGNOR TO AKTIENGESELLSCHAFT FUER FEINMECHANIK VORMALS JETTER & SCHEERER, OF TUTTLINGEN, GERMANY, A CORPORATION OF GERMANY.

HAIR-CLIPPING MACHINE.

Application filed April 18, 1922. Serial No. 554,976.

To all whom it may concern:

Be it known that I, CHRISTIAN C. SCHEERER, a citizen of the Republic of Germany, residing in Tuttlingen, Wurttemberg, Germany, have invented certain new and useful Improvements in Hair-Clipping Machines, of which the following is a specification.

This invention relates to hair clipping machines, and has for one object to improve generally the simplicity and efficiency of such devices and to provide a device or apparatus of this kind in which the main cutting blade is easily securely fastened and easily detached from the machines for replacement, sharpening or interchange with different thicknesses of blade.

Another object of the invention is to provide an apparatus or device of this kind which may be easily assembled and disassembled generally.

Another object of the invention is to provide an apparatus or device of this kind in which the cutting edges may be easily sharpened.

Another object of the invention is to provide an apparatus or device of this kind in which the pressure of engagement of the cutting edges may be easily adjusted.

For the accomplishment of these and other objects my improved clipping machine comprises, briefly stated, a main supporting member comprising a plate portion carrying a handle fast thereon, and a movable toothed cutting blade beneath the plate portion. A lower toothed cutting blade is slidably detachably fastened on the lower face of the plate portion and has teeth engaging under the teeth of the movable blade in cutting relation therewith. A movable handle is pivoted on the plate portion and engages said movable blade, and is held in one position of movement by a helical spring adjusted by a suitable adjusting screw plug. A cover shell suitably engaged by an adjusting nut, bears on the movable blade and holds it in good cutting contact with the fixed blade.

A spring latch carried on said plate portion, engages a notch in the lower blade and holds the latter in place.

Other objects of the invention will appear as the description proceeds; and while herein details of the invention are described, the invention is not limited to these, since many and various changes may be made

without departing from the scope of the invention as claimed. 55

In the accompanying drawing, showing by way of example one of many possible embodiments of the invention,

Figs. 1 and 2 are respectively plan and side elevation of the clipping machine assembled; 60

Figs. 3 and 4 are respectively fragmental plan and side elevation of the main supporting member of the machine; 65

Figs. 5 and 6 are respectively fragmental plan and side elevation of the movable handle;

Figs. 7 and 8, are respectively vertical section and plan of the cover shell; 70

Figs. 9 and 10 are respectively end and face elevations of the movable blade;

Figs. 11 and 12 are respectively end and face elevations of the lower blade.

Fig. 13 is a side elevation of the helical spring; 75

Fig. 14 is a side elevation of the screw plug;

Fig. 15 is an edge and a face elevation of the spring washer. 80

Fig. 16 is a side elevation of the adjusting pressure nut.

Figs. 17 and 18 are respectively bottom plans showing different positions of the movable cutting blade; 85

Fig. 19 is a bottom plan of the machine with lower plate removed;

Figs. 20 and 21 are respectively plan and edge elevations of the lower blade; and

Figs. 22 and 23 are respectively face and edge elevations of the spring latch. 90

The various parts of my new machine are carried on a main supporting member comprising a plate portion 10 (Fig. 3), a cylindrical spring guide 11 on the rear edge of the plate member, a post 12 standing on the mid-part of the plate member, and a fixed handle 13 extending rearwardly and upwardly from the upper part of the guide. The lower face of said plate member 10 is provided rearwardly with a transverse under-cut guide rib 15 (Fig. 4) and at the forward part with a transverse guide recess 16, and guide lugs 17 depending in opposite ends of said recess and guiding a movable cutting blade 20 (Fig. 10) slideable in said recess 16 and provided with forwardly projecting cutting teeth 21 and at each end

with guide slots 22 for receiving said lugs 17. The lower face of said blade 20 has a wide groove 25 extending from end to end to provide off-set forward and rear lower bearing faces 26 and 27.

A lower cutting blade 30 (Fig. 12) disposed beneath said upper blade and plate portion is provided at the forward edge with forwardly projecting cutting teeth 31 engaging said teeth of the upper plate, and at the rear part with a wide undercut groove 32 (Fig. 11) receiving said rib 15 to hold said blade in place, and to permit the lower blade to be removed by sliding the latter 15 along the rib. The forward part of the face of said lower blade has a wide groove 33 providing offset bearing faces 34 and 35 engaging respectively said offset bearing faces 26 and 27 of the upper plate, to reduce the bearing surface and maintain close engagement between the teeth 21 and 31 of the blades. A spring latch 38 (Figs. 3, 4 and 23) anchored at its forward end on and passed rearwardly over said plate portion 10 engages in notches 39 and 40 (Figs. 3 and 20) provided respectively in the rear edge of the plate portion 10 and the lower blade 30, and then turned rearwardly to form a manipulating portion. The rear 30 end of the spring may be raised to remove the spring from the notch 40, thereby to permit the removal of the blade.

The movable handle 44 (Fig. 5) of the machine is pivoted near its forward end on said post 12 and has a forwardly projected down-turned finger 46 projecting through the cut-away recess 45 in the portion 10 and engaging in an actuating notch 47 of the blade 20 to reciprocate the latter.

An adjusting screw plug 48 (Fig. 1) is disposed in the interiorly threaded outer end of said spring guide 11; while a plunger disk 49 is loosely disposed in the inner end of said guide in engagement with a projection 50, Fig. 17, on the handle 44 just to the rear of said post. A spring 51 (Fig. 13) is compressed between said disk and plug, whereby the movable handle 44 and upper blade 20 are yieldably moved by the 45 spring to one limit of their movement. The part of said movable handle 44 just to the rear of said post engages under an overhanging portion 52 (Fig. 3) formed by a slot in said guide 11, whereby the movable handle is held in place.

A cover shell 55 (Fig. 8) disposed over said plate portion 20 is provided with a positioning opening 56 receiving said post 12, and a downwardly pressed projection 57 engaging in a positioning perforation 58 (Fig. 1) in said cylindrical guide 11. A pair of downwardly disposed bearing lugs 60 disposed at opposite ends of the forward edge of said cover press on said upper blade 20.

A spring washer 61 received on the post 12 and pressing on the cover 55 is pressed upon by a pressure nut 62 received on the post 12, thereby to press said bearing lugs 60 on the upper blade thus adjustably to press the blades 20 and 30 together.

The machine is normally operated in the ordinary way. If the pressure of the spring 51 is too weak or too strong, the plug 48 is adjusted in order to compress the spring the right amount; and the spring may be removed, as for replacement, merely by removing the plug.

Pressure of engagement between the teeth of the blades is regulated by adjusting the nut 62. The lower plate 30 may be removed or interchanged by merely raising the spring 38, as explained, and sliding the lower plate off, as illustrated in Fig. 19, but the nut 62 should first be loosened, in order to relieve the pressure on the movable blade.

When the lower blade is removed, the movable blade may be removed, and this permits the finger 46 to move leftward in the slot 45 until the handle 44 clears the overhanging portion 52 (Fig. 3) whereupon the handle 44 may be easily slipped from the post 12, the nut 62 and shell cover 55 first having been removed.

I claim as my invention:

In a hair cutting device, the combination with a main supporting member, of an upstanding post on said supporting member, a cylindrical spring guide member on the rear edge of said supporting member, said guide member being provided with a positioning slot at the top thereof, a movable toothed cutting blade adapted to be positioned beneath the supporting member, a fixed lower toothed cutting blade co-operating with and engaging under the movable blade; a movable handle pivoted on said post and engaging said movable blade; a spring member in said guide co-operating with said movable handle; a cover shell disposed over said blade portion and provided with a positioning opening receiving said post, forward bearing lugs on said cover shell pressing on said movable blade; and a downwardly pressed projection on said cover shell engaging in the perforation of said spring guide; a pressure nut on said post for pressing the bearing lugs on said movable blade; and a flexible clasp extending rearwardly on said main supporting member, said clasp having an off-set portion in resilient contact with a notch in the cutting blade whereby to retain the same in cooperative relation with the main support.

CHRISTIAN C. SCHEERER.
